NATHANIEL S. SEELEY, OF FLUSHING, AND FRANKLIN PERRY, OF ELMHURST, NEW YORK.

DUPLICATOR.

1,235,933.

Specification of Letters Patent. Patented Aug. 7, 1917.

Application filed February 10, 1917. Serial No. 147,758.

To all whom it may concern:

Be it known that we, NATHANIEL S. SEELEY and FRANKLIN PERRY, citizens of the United States, and residents of Flushing, 5 county of Queens, and State of New York, and Elmhurst, county of Queens, State of New York, respectively, have invented certain new and useful Improvements in Duplicators, of which the following is a description.

Our invention relates particularly to duplicators of the portable type.

One object of our invention is to provide such a duplicator which shall be as small 15 and compact as possible, convenient in operation and of relatively inexpensive construction.

Another object of our invention is the provision of improved transfer-ribbon supporting means, which permit of ready adjustment of the ribbon while in operative position, and which can be easily removed from the duplicator to facilitate renewal of the ribbon when desired.

Another object of our invention is the provision of improved means to facilitate the tearing off of sheets from a web or webs of paper.

Another object of our invention is to provide a duplicator of the type above referred to, with means for detachably supporting a book, such as an order book, in full view of the operator, so that he may have ready reference thereto while using the duplicator, 35 and with convenient means for receiving and retaining one or more of the duplicate slips of each set produced upon the duplicator.

Other objects of our invention, such as the provision of means for registering the web properly prior to the tearing of sheets therefrom, and of means for preventing the displacement of the transfer ribbon by the paper webs when the latter are advanced, 45 will be referred to more fully hereafter.

In the drawing:

Figure 1 shows our improved duplicator in perspective;

Fig. 2 is a vertical longitudinal section 50 thereof;

Fig. 3 is a perspective view of the combination writing table and ribbon support which we employ in our duplicator;

Fig. 4 is a fragmentary view looking from 55 the bottom of the forward end of the du-

plicator cover, and showing the means for registering the paper web;

Fig. 5 is a fragmentary sectional view taken on the line 5—5 of Fig. 4; and

Fig. 6 is a fragmentary view of the rear 60 end of the duplicator, showing the book-secur ing lips.

Referring to the drawing, 10 indicates the paper receptacle which is preferably of substantially rectangular shape and adapted to 65 receive a supply of paper 11. The paper supply, as shown, is in the form of two superposed webs folded in a zig-zag manner, though obviously, if it is desired, more than two webs may be employed. We have found 70 that by arranging the webs as indicated, we are enabled to store a maximum supply of paper in a minimum space.

Within the receptacle 10, adjacent the front end thereof, there is removably placed 75 the combination writing table and transfer-ribbon supporting means indicated at 12, and best shown in Fig. 3. This device includes the writing table 13, the side edge portions of which are bent down, as clearly 80 shown in the drawing, and provided with lips 14, each of which is constructed to form a bearing for one end of a ribbon spool 15. Each of the ribbon spools 15 is provided with a knurled head or similar member, as 85 indicated at 16, these heads being arranged to project without the receptacle 10 through slots in the front wall thereof, so that they are readily accessible to adjust the ribbon 17 when the device 12 is in operative position 90 within the receptacle.

The cover 18 of the receptacle 10 is readily removable, and when it is desired to remove the device 12 from the receptacle for any reason, such as to renew the ribbon 17, 95 this may be readily accomplished by first removing the cover 18. As is evident from an inspection of Fig. 3, when the device 12 has thus been removed, it is an easy matter to remove and replace the ribbon spools 100 15 and the ribbon 17. The removable cover 18 is provided, as indicated, with an aperture 19 which, when the cover is in position, lies above the writing table 13. This cover is also provided at its front end with an 105 extension 20 which carries at its end a knife edge 21 which will be described more in detail hereafter.

In the ordinary operation of our improved duplicator, the ends of the superposed webs 110

pass over the writing table 13, the transfer ribbon 17 being interposed between the upper and lower web. The rear end of the writing table 13 is preferably rounded as indicated at 22, to facilitate the passage of the webs thereover. The desired notation is written upon the portion of the upper web which underlies the aperture 19 of the top 18, and through the action of the transfer ribbon 17 this notation is transferred to the underlying portion of the lower web. This having been accomplished, the two webs are advanced together by manually pulling their exposed ends forwardly, and after they have been advanced the desired amount, the portions thereof which have been written upon are torn off against the knife edge 21, above referred to.

In order to render the ends of the web more accessible after sheets have been torn off as above described, the knife edge 21 is preferably displaced from the position ordinarily assumed by the ends of the web projecting through the opening formed between 25 the front of the writing table 13 and the front of the cover 18. The knife edge may be thus positioned in any desired way, but we preferably provide the cover 18 with a knife-edge carrying extension 20 which is 30 inclined in an upward and forward direction. By the term "inclined", we mean to describe an extension which may lie in an inclined plane as well as the curved extension illustrated in the drawing. The fact 35 that the knife edge 21 is thus displaced, does not in any way interfere with the tearing off of sheets from the webs, since after the initial advance of the webs, the natural tendency in pulling them out and tearing off 40 sheets therefrom, is to hold the webs up against the knife edge.

In order that the webs, in passing beneath the aperture 19 of the cover 18, may be maintained in proper lateral register, we 45 preferably provide the forward end of the cover 18 with depending side guides, such as shown at 23 in Figs. 4 and 5. Also, in order that the web may be advanced a proper distance each time before sheets are torn therefrom, we provide projections 50 adjacent the knife edge 21, these projections being adapted to fit into suitably shaped notches 25 in the paper webs, which as above indicated are held up against the knife edge 55 extension after their initial advance.

We have found that unless some means be provided for relieving the frictional contact between the paper webs and the transfer ribbon interposed therebetween, the advancing 60 of the webs is apt to cause a forward displacement of the ribbon, which is objectionable. We have, therefore, conceived the idea of relieving the frictional contact between the webs and the ribbon by employing 65 means such as the bridge member 13^a which

may be secured to the writing table 13 at a point adjacent the edge of the ribbon 17. The lower web of paper passes below this bridge 13^a and the upper web of paper passes above it, the result being to overcome 70 any tendency that the webs may have to stick together and to prevent their displacing the ribbon 17. This bridge 13^a also, by co-operation with the table 13 and the cover 18, serves as a brake tending to retard the 75 advance of the paper webs, and thus facilitates the tearing off of sheets therefrom, as will be readily understood.

In the use of a portable duplicator such as above described, it frequently is found necessary to provide some means for storing one or more of the slips of each set of duplicates produced. The usual method, when there is no desk or filing facility at hand, is for the operator to place these duplicates in his 80 pockets or in his order book. In order to eliminate the obvious objections to these methods, we have provided our improved duplicator with a storage device. As shown in the drawing, this device includes a trough-shaped member 26 secured to the bottom of the receptacle by a spring 27, or in any other desired manner. The spring 27 shown in the drawing normally forces the bottom plate of the trough-shaped member 26 against the 85 bottom of the container and is thus adapted to hold between itself and the bottom of the container, all slips which may be placed therein. Fig. 2 of the drawing shows this device 26 moved away from the bottom of 90 the container, so that slips may be placed therein. This movement may be accomplished in any desired manner, but in order that it may be done by the hand with which the operator supports the device, we preferably provide the rear end of the device 26 with a depending flange or lever 28. It is 95 obvious that pressure against this flange or lever 28 will move the forward end of the device 26 away from the bottom of the receptacle 10.

To use a portable duplicator to best advantage, it is frequently necessary that the operator have ready reference to an order book or the like. To provide for this, we 115 have supplied our duplicator with means for detachably holding a book, such as an order book or pad, in open condition in full view of the operator. As illustrated, these means comprise two pairs of lips 29 and 120 30, one pair, such for example as the pair 29, being preferably stationary, and the other pair, such as 30, being preferably spring-pressed toward the first pair. All of these lips are adapted to embrace the edges of the 125 book or pad cover, as indicated in Fig. 1. As shown herein, the stationary lips 29 are formed integrally with the cover 18 of the duplicator, and the lips 30 are mounted on a 130 sliding plate 31, which is adapted to con-

- tact with the under surface of the cover 18, and which is normally spring-pressed toward the lips 29 by means of a spring 32 connected to one of a pair of lugs 33 depending from the plate 31. This spring reacts against the adjacent depending end of the cover 18, or against the rear wall of the receptacle 10. The cover 18 is provided with slots 34 through which the lips 30 project.
- 10 In certain of the claims which follow, the term "open book" is used and is intended to refer not only to a book of the ordinary type, but as well to a pad or any similar device which can be conveniently used for reference by a person employing our improved duplicator.

It is to be understood that the terms "forward" and "rear", as used in the specification and claims with reference to the two ends of the duplicator and of its component parts, are employed merely for convenience to designate the end from which the paper is discharged and the opposite end respectively. These terms have no relation whatever to the position of the duplicator with respect to the operator, it being apparent that duplicators constructed in accordance with our invention, may be adapted when in use to be held with the paper discharge end extending either toward or away from the operator or to his right or left.

While we have illustrated and described but a single embodiment of our improved duplicator, it is to be understood that we do not wish to limit ourselves to this particular form of duplicator, since obviously many changes may be made therein without departing from the spirit of our invention.

What we claim is:

- 40 1. A duplicator, comprising a substantially rectangular receptacle for paper, and a writing table removably mounted within said receptacle and removable therefrom while the paper is retained in the receptacle, said table being provided with means for supporting a transfer ribbon and with means normally projecting without said receptacle, for advancing the ribbon while the table is in operative position within said receptacle.

2. A duplicator, comprising a substantially rectangular receptacle for paper, a writing table removably mounted within said receptacle and removable therefrom while the paper is retained in the receptacle, said table being provided on each side thereof with bearings, ribbon carrying spools mounted in said bearings and manually operable members connected to said spools and

normally projecting without said receptacle, 60 whereby the ribbon may be advanced while the table is in operative position within said receptacle.

3. A duplicator comprising a paper receptacle, a cover therefor, said receptacle being provided at its forward end with an aperture through which the paper normally projects in a plane substantially parallel to said cover, and with an extension inclined forwardly and away from the plane of the paper, and bearing a knife edge at its forward end.

4. A duplicator, comprising a paper receptacle provided with a cover, said cover having at its forward end a forwardly and upwardly inclined knife-edge carrying extension, for the purpose described.

5. A duplicator, comprising a receptacle for a web of paper having spaced notches in its edges, said receptacle being provided at one end with an opening through which the paper may project and be withdrawn, a knife edge for tearing off sheets from said webs, and projections located adjacent said knife edge and adapted to be received within said notches, to register said webs prior to the tearing operation, said knife edge and projections being displaced from the plane normally assumed by paper projecting through said opening.

6. A duplicator, provided with a receptacle for a plurality of superposed webs of paper, means removably mounted in said receptacle for supporting a transfer ribbon in position between portions of said webs, 95 said ribbon supporting means being removable from the receptacle while the webs are retained in the receptacle, and means carried by said ribbon-supporting means for relieving the frictional contact between said webs and said ribbon, whereby the webs may be advanced with respect to said ribbon without displacing the latter.

7. A duplicator, provided with a receptacle for a plurality of superposed webs of paper, means removably mounted in said receptacle for supporting a transfer ribbon in position between portions of said webs, said ribbon-supporting means being removable from the receptacle while the webs are retained in the receptacle, and a bridge carried by said ribbon-supporting means adjacent the ribbon, and adapted to separate said webs, thereby to relieve the frictional contact between said webs and said ribbon, and retard the advance of said webs.
